(57) **CLAIM**

The ornamental design for a microscope, as shown and described.

DESCRIPTION

FIG. 1 is a front perspective view of the microscope showing the new design;

FIG. 2 is another front perspective view thereof;

FIG. 3 is a left perspective view thereof;

FIG. 4 is a right perspective view thereof with the side elements in a position similar to FIG. 3; and,

FIG. 5 is another left perspective view thereof, wherein side elements are in a closed position of use.

1 Claim, 5 Drawing Sheets
